AUTOMOBILE WHEEL COVER

Robert Grove, Birmingham, and William D. Steere,
Rochester, Mich., assignors to Chrysler Corporation,
Highland Park, Mich., a corporation of Delaware

Filed Nov. 12, 1963, Ser. No. 77,352

Term of patent 7 years

(Cl. D14—30)

The dominant features of our design reside in the full line portions of the drawing.

We claim:

The ornamental design for an automobile wheel cover, substantially as shown and described.
